UNITED STATES PATENT OFFICE

JOHN EDWARD DIGGLE, OF DANNEVIRKE, NEW ZEALAND

STROPPING DEVICE

Application filed June 14, 1928, Serial No. 285,422, and in New Zealand March 6, 1928.

This invention relates to stropping devices for attachment to safety razors.

The object of the present invention is to provide a convenient form of such device which may be readily attached and detached from the safety razor.

According to my invention, the stropper comprises a cross-piece having members which are simply slid between the guard member and backing member of a safety razor and held therein by tightening the handle of the razor in the same way as the blade is held. Mounted in this cross piece is a roller beneath which the strop is passed. This roller gears with a spindle which carries members which open to receive the razor blade. These two members are adapted to be locked together by a clip in order to retain the blade in position between them. The action of the device is that as the razor is moved in one direction along the strop, the roller will tend to be rotated by the strop and will cause the members carrying the blade to be forced down upon the strop to sharpen one side of the blade, and when the razor is moved in the other direction the members carrying the blade will be rotated over to the opposite position so as to sharpen the other side of the blade.

The invention will now be described with the aid of the accompanying drawings, wherein:—

Figure 1 is an end elevation of the stropper attached to a safety razor, while

Figure 2 is a side elevation thereof.

Figure 3 is a perspective view of the cross piece.

Figure 4 is a cross section of the cross piece and blade holding members.

Figure 5 is a side elevation partly in section.

Figure 6 is a side view, and

Figure 7 is an end view of a blade holding member.

Figures 8 and 9 show two views of a clip for holding the blade in position.

Referring to the drawings, the device consists of a cross piece 1 having internally bent flanges 2 running the length of the cross piece which are adapted to fit between the guard member 3 and backing member 4 of a safety razor of the type shown. The end of the cross piece has brackets 5 turned upwards, while a roller 6 is mounted between the brackets 5, the reduced end forming the spindle of such roller at one end projecting through a bracket and having a toothed wheel 7 fixed thereon, the strop 8 being arranged to pass between the roller 6 and the top of the cross piece 1 and ride over rounded portions 9 (see Figures 1 and 4). The space between the roller and the cross piece is such that the strop when drawn through this space will rotate the roller, but may still be drawn through when the roller cannot rotate any further.

The blade holder consists of two flat members 10 and 11, the member 10 being secured to a spindle 12 mounted to rotate in the brackets 5 and having on one end a toothed wheel 14 gearing with the toothed wheel 7. The other member 11 is hinged freely on the spindle 12 so that the two members 10 and 11 open out in a hinge-like manner.

Projecting from the member 10 are a number of studs 15 adapted to pass through holes 16 in the member 11, so that when a blade 23 of the razor that is to be stropped is inserted between the two members 10 and 11, the studs 15 pass through the holes in the blade. In order to retain the blade of the razor firmly grasped between the two members 10 and 11, such two members are adapted to be locked together by a clip 18 pivoted at 19 on the member 11. This clip 18 has an arcuate opening 20 through which projects a pin 21 from the central stud 15. The head of the pin is larger than the arcuate slot 20, but such slot ends in an opening 22.

slightly larger than the head of the pin. When the blade of the razor is inserted in position between the two members 10 and 11, the clip 18 by being moved over to the position shown in Figures 5 and 8, will retain the two members 10 and 11 firmly together and the blade in a rigid position. When, however, it is desired to remove the blade, the clip 18 is moved to the position shown in Figure 9, and the two members may then be opened and the blade removed.

In operation, the strop is passed beneath the roller 6 and the cross piece 1 and by moving the razor in the direction of the arrow in Figure 1, the members 10 and 11 carrying the blade will be forced by the action of the roller 6 on to the strop as shown, and when the handle is moved in the other direction, the members 10 and 11 will then move over to the position shown in dotted lines in Figure 1, thus sharpening the other side of the razor blade.

To remove the stropping device, the handle of the razor is simply unscrewed and the cross piece will slide out from between the guard member and the backing member.

What I claim is:—

1. A stropping device for attachment to safety razors having guard and backing members, comprising a cross piece having members to engage between the said guard and backing members, bearing brackets projecting upwardly from the cross piece adjacent the ends thereof, a roller pivoted in said brackets and beneath which the strop is passed internally of the bearing brackets, a spindle also mounted between the said bearing brackets, and adapted to be rotated by the said rollers, and additional members on said spindle for carrying the razor blade and adapted to bear on one side of the strop when the razor is moved in one direction, and to then bear on the other side when the razor is moved in the other direction, the said member of the cross piece comprising internally bent longitudinal flanges adapted to be inserted in endwise direction between the longitudinal extremities of the said guard and backing members.

2. A stropping device for attachment to safety razors having guard and backing members, comprising a cross piece having members to engage between the said guard and backing members, bearing brackets projecting upwardly from the cross pieces adjacent the ends thereof, a roller pivoted in said brackets and beneath which the strop is passed internally of the bearing brackets, a spindle also mounted between the said bearing brackets, and adapted to be rotated by the said rollers, members on the spindle for carrying the razor blade and adapted to bear first on one side of the strop when the razor is moved in one direction, and then to bear on the other side when the razor is

moved in the opposite direction, to produce relative motion between the razor and the strop, and means for locking the blade between the said last mentioned members, the said members of the crosspieces comprising internally bent longitudinal flanges adapted for insertion in endwise direction between the longitudinal extremities of the side guard and back members.

In testimony whereof, I have signed my name to this specification.

JOHN EDWARD DIGGLE.
